UNITED STATES PATENT OFFICE.

RALPH E. HOUGHTON AND MICHAEL J. HANLON, OF CLIFTONDALE, MASSACHUSETTS.

ILLUMINATING DEVICE FOR ELECTRIC FIXTURES.

1,227,144.

Specification of Letters Patent.

Patented May 22, 1917.

Application filed August 22, 1916. Serial No. 116,363.

To all whom it may concern:

Be it known that we, RALPH E. HOUGHTON and MICHAEL J. HANLON, both citizens of the United States, and residents of Cliftondale, in the county of Essex and State of Massachusetts have invented a new and Improved Illuminating Device for Electric Fixtures, of which the following is a full, clear, and exact description.

10 Our invention relates to a luminous device for electric fixtures, and is more particularly intended for embodiment in a pendant attachable to a pull-chain or the like. The device includes means for securing the same to the chain, and luminous material, together with glass elements in a circular series about the luminous surface. The glass elements preferably are exact cylinders or elements approximately cylindrical in cross section and are tangent to a cylindrical surface bearing the luminous material so that by reason of the cylindrical surfaces the light will be magnified as seen from any angle.

25 Prime objects in view in the production of our device are to obtain the maximum illumination from the luminous material and to produce an effective luminosity from a minimum quantity of luminous material, whereby high grade and expensive material may be employed without unduly increasing the cost of manufacturing the device.

Other objects of the invention are to provide retaining means for the glass elements 35 of a character to permit of sections of a glass rod being employed and effectively retained regardless of variations in the diameter of the glass rod; to provide a device that may be securely attached to the chain 40 with facility; and generally, to provide a construction involving few parts of simple forms that may be readily assembled.

The invention will be particularly explained in the specific description following.

45 Reference is to be had to the accompanying drawings forming a part of this specification in which similar reference characters indicate corresponding parts in all the views.

Figure 1 is a perspective view of our improved illuminating device;

Fig. 2 is a central longitudinal section on a larger scale;

Fig. 3 is a cross section on the line 3—3, Fig. 2;

Fig. 4 is a cross section on the line 4—4, 55 Fig. 2;

Fig. 5 is a perspective view of a fastener element forming part of the device, and engageable with the terminal of the pull chain.

In carrying out our invention in accordance with the illustrated example, a tubular core or center 10 is formed preferably from brass tubing and having a bore to permit the ready passage therethrough of balls 11 or equivalent elements of a chain 12. To the 60 ends of the tube 10 heads 13 are secured in any suitable manner as by riveting or flanging over the tube as at 14, Fig. 2.

Glass cylinders 15 are disposed in an annular series about the tube 10 parallel with 70 the axis of the tube and tangent with the latter. The ends of the heads 13 are formed with conical flanges 16 to receive the ends of the cylinders 15. The conical form of the flanges accommodates cylinders of varying 75 diameter and therefore we may produce the cylinders 15 from ordinary commercial glass rods, the diameter of which may not be uniform.

The tube 10 constitutes a base to receive 80 luminous material 17 which is applied thereto as a coating. Any approved luminous material may be utilized, for example, phosphorescent calcium sulfite or what is known as radiumized material. The latter materials are more expensive but have higher illuminating properties and greater permanency, and we are enabled to employ the same without unduly increasing the total cost of manufacturing the device owing to 85 the comparatively small area of the tube 10, the effect of the elements 15 serving to give the necessary illumination so that the device when attached to a pull-chain will be distinctly luminous in the dark. 95

To attach the device to a chain 12, we employ a hollow fastener plug 18, said plug being open at the outer end and having a dome shape at the inner end. For the major portion, the plug 18 is cylindrical to 100 be snugly received in the cylindrical bore of the tube 10. The outer end of the plug is flanged as at 19 to contact with the adjacent head 13 and limit the inward movement of said plug. At one side, a slot 20 105 is produced in the plug to pass across the center of the dome shaped inner end. Said slot accommodates a link 12 or equivalent

element of the chain so that a ball 11 or like protuberant part of the chain may be passed into the hollow interior of the plug 18 and bear against the inner side of the dome thereof.

It is to be understood that in practice the usual acorn or other pendant on the chain is removed and our improved device applied to the chain instead.

10 Having thus described our invention, we claim as new, and desire to secure by Letters Patent:

1. An illuminating attachment of the class described including a cylindrical tubular core adapted to receive a pulling medium, means associated with the core to connect the same with a pulling medium, a coating of luminous material on said core, cylindrical glass elements in a circular series 15 about the said coated core, tangent thereto, and heads on the core having conical flanges clamping the said cylindrical elements in position.

2. An attachment of the class described 25 including a cylindrical core, heads on the core, an exterior coating of luminous material on the core, circular series of glass elements about the coated core, means to clamp said elements at their ends, and 30 means to connect the attachment with a fixture.

3. An attachment of the class described including a core, luminous material on said core, and a series of glass elements about 35 said luminous material.

4. An attachment of the class described including a core, luminous material on said core, a series of glass elements about said

luminous material, and heads on the said core having flanges clamping the said elements.

5. An attachment of the class described, including a tubular core having a bore of a diameter to receive a pull-chain, a hollow plug fitting one end of the core and slotted 45 at a side thereof for receiving a chain link, the interior of the plug accommodating a relatively larger member of the chain than the said slot, luminous material about the core, and glass elements about the said 50 luminous material.

6. An attachment of the class described including a tubular core adapted to receive a pull-chain, a hollow plug fitting one end of the core, a slot at a side thereof for receiving a chain link, the interior of the plug accommodating a relatively larger member of the chain than the said slot, said plug having a radial flange bearing against the adjacent end of the core, the 60 said slot extending through said flange and transversely in the body of the plug beyond the center of the latter, luminous material about the core, glass elements about the said luminous material, and means to hold said 65 glass elements in position.

7. An attachment of the class described including a core, luminous material about the core, and a series of glass cylinders about the said material.

RALPH E. HOUGHTON.
MICHAEL J. HANLON.
